RECTIFIER ARRANGEMENT FOR SWITCHING PURPOSES

Otto Tschumi, Soleure, Switzerland, assignor to
Autophon Aktiengesellschaft, Soleure, Switzerland, a joint-stock company of Switzerland

Application May 12, 1944, Serial No. 535,295
In Switzerland December 4, 1942

Section 1, Public Law 690, August 8, 1946
Patent expires December 4, 1962

1 Claim. (CL. 171—97)

1

This invention relates to rectifier arrangements for switching purposes. Rectifier arrangements for switching purposes which can be connected with current consuming elements quite independent of the kind and direction of current (so-called single-phase Grätz-full path-rectifier arrangements) are well-known. In different connections it has been found desirable to provide similar simple arrangements which are not only independent of the kind and direction of current, but have valve qualities.

The rectifier arrangement according to the invention is characterised in that, besides the means serving exclusively for rectifying, it comprises current consuming elements independent of the kind and direction of current and others which are dependent on the kind and direction of current.

The accompanying drawings illustrate, by way of example, in

Fig. 1 the diagram of an embodiment of the device according to the invention and in

Fig. 2 the diagram of an example of the use of this device.

In Fig. 1 the terminals are designated by the reference characters 1 and 2. Between these terminals is connected a Grätz full path-rectifier arrangement with rectifier elements a, b, c, d arranged in a square, opposite corners of the square being connected with the terminals 1 and 2. A current consuming element which is independent of the kind and direction of current is connected across the corners of the square other than those with which the terminals 1 and 2 are connected. The current consuming element II is connected in series with the rectifier element a and parallel to the rectifier element c, while the current consuming element L is in series with the rectifier element b and parallel to the rectifier element d. The two current consuming elements may, e. g., be constituted by a relay winding (II) and a visual signal in the form of an electric lamp (L).

The manner of operation of the arrangement according to the invention is that, in the case of a direct current with the positive pole 1 and the negative pole 2, a path of direct current is formed over +—1—a—I—d—2—... and a parallel path over +—1—a—II—2—... Upon reversal of the poles, the two following parallel paths are provided: +—2—c—I—b—1—... and +—2—L—b—1—... The resistance of one of the current consuming elements being always greater than that of the rectifier element connected in parallel thereto, the following circuits occur for the two service conditions with

2

regard to the elements II and L: If terminal 1 is positive: +—1—a—II—2—; if terminal 2 is positive: +—2—L—b—1—. From this it may be seen that, independent of the change of polarity of the terminals 1 and 2 the current always passes in the same direction through the current consuming element I, while the current consuming element II only carries current when the pole is positive and the current consuming element L carries current when the pole 1 is negative. In this simple rectifier arrangement one succeeds in connecting both elements independent of the kind and direction of current and also elements dependent on the kind and direction of current, so that this arrangement has the features of a continuous contact as well as of a valve.

If an alternating current is used, the current consuming element I receives the whole current, while the two others absorb only half a period, which fact in the example shown, would result only in a flashing of the lamp L at half luminous intensity.

The example of the use illustrated in Fig. 2 of the device according to the invention is in a subscriber's device for selectively loud or faintly audible traffic, the change of the speaking direction in the case of loud traffic being manually effected.

EW is a transducer which can be switched so as to work as a receiver or as a transmitter. This transducer is connected with the transformer UE through an amplifier V having an input transformer E and output transformer A and a circuit closer e_1 for connecting the amplifier with a source of alternating current. The amplifier V can be connected to the transducer EW in both directions by the relay contacts u_1 and u_2 . The center point of the winding of the transformer UE on the line side is connected with one free end (terminal a) of the winding through the telephone receiver T and the contact TK_1 while bridging-over one half of the winding. Between the winding ends connected to the transmission conductors a, b and impedance coil Dr is placed, the center point of which is grounded through the contact ES, the contact e_2 , the device according to the invention, and the impulse contact i of the calling dial NS. The contacts ES and e_2 are bridged-over by the condenser CI, while over the condenser CII and the visual signal TZ, the middle of the impedance coil Dr is directly connected with the impulse contact i .

The arrangement has here, too, a Grätz-full-path-rectifier arrangement comprising four rectifier elements connected to one another in a

known manner. As a current consuming element which is independent of the kind and direction of current, a relay E is provided, the center point of which is connected with the off-normal contact k of the calling dial NS. The elements dependent on the kind and direction of current are the relay U, the visual signal SZ and the resistance W₃; U and SZ, on the one side, and W₃, on the other side, being connected in parallel to differently directed rectifier elements. The relay U can be disconnected by the switch hook TK₂ and the resistance W₃ by the switch hook TK₃. The contacts e₁ and e₂ are contacts of the relay E and are closed when the relay is energized. The contacts u₁ and u₂ are contacts of the relay U. The switches TK₁, TK₂ and TK₃ are hook switches of the telephone receiver T.

The manner of operation of the arrangement shown is as follows:

On a call of the illustrated subscriber's device two current sources not shown connected in series are in relation with the terminals a and b. These two sources consist of an alternating current source and a direct current source whose negative pole is connected to the terminals. Owing to the open position of contact e₂ and to the illustrated connection of the condensers CI and CII a direct current path is not formed initially, but an alternating current circuit is established from the grounded alternating current source over the impedance coil Dr and from here, on the one side, over CI and the device according to the invention and, on the other side, over the condenser CII, the visual signal TZ and then, together, over the impulse contact i to ground. The alternating current has the effect that the relay E, being independent of the kind and direction of current, is energized. Likewise, the relay U and the visual signals SZ and TZ respond, while a polarised direct current flows through the resistance W₃. By the action of relay E, the contacts e₁ and e₂ are closed, so that the amplifier V is switched-in and a direct current path is provided over impedance coil Dr—contacts ES—contact e₂—the device according to the invention-impulse contact i and from here to ground. If the alternating current source is now disconnected, the relay E being an element independent of the kind and direction of current relay U and the visual signal SZ remain in their former operating conditions; resistance W₃ carries no current and the visual signal forming an electric lamp TZ is extinguished. The action of the relay U causes the operation of the relay contacts u₁ and u₂, whereby the subscriber's station is changed-over from the represented operating condition for speaking to that for listening. With the aid of a means, which is not the object of the present invention, the poles of the direct current source are interchanged, i. e., in place of the positive pole which has been grounded till now, the negative pole is connected with ground and the positive one with the terminals a, b. Owing

to this pole-changing, relay E remains in its operating condition, while relay U drops and the electric signal lamp SZ is extinguished. Thereby, the position of the switches u₁ and u₂ is again changed, the speaking direction altered and the illustrated subscriber's station again brought into the operating condition for speaking. It is thus possible in the arrangement shown to alter by a simple pole-changing the speaking direction and to control a visual signal, while, in spite of this, the rectifiers remain constantly switched-in.

If the subscriber now uses the telephone receiver T, the switch hooks TK₁, TK₂, TK₃ are operated. Closing switch hook TK₂ results in a reduction of current, while on opening the other two switch hooks TK₂ and TK₃ the relay U and the resistance W₃ are finally disconnected. By this reduction of current means are operated in the main station, allowing a weaker alternating current to be superimposed on the direct current. The visual signal TZ comes into action and informs the other station that the subscriber uses the receiver. Since relay U is definitely disconnected, the speaking direction can no longer be changed, and the transducer EW remains constantly connected as transmitter. A change in the direction of current is, therefore, quite immaterial for the subscriber using the receiver but has only an influence upon the device of that subscriber who desires to have a loud conversation. When the latter is finished the calling station operates the contact ES. Thereby the direct current is interrupted, relay E drops and opens the contacts e₁, e₂, contact e₁ thereby disconnecting the rectifier, and contact e₂ finally interrupting the direct current path.

Therefore, with the arrangement according to the invention, the switching-over of the speaking direction is locked for the subscriber desiring a faintly audible traffic, while for the subscriber wishing to use the loud speaker, it remains quite intact. Besides this, the same device lets the subscriber know by a visual signal that the faintly audible traffic is in use.

What I claim is:

In an electro-acoustic circuit, a switching and signal device comprising a full wave rectifier comprising four rectifier elements connected in a square with opposite rectifier elements reversed in direction, means for connecting one pair of opposite corners of said square with a line carrying signal current, a relay connected across the other pair of opposite corners of the square and responsive to line current in both directions, a second relay connected in parallel with one of said rectifier elements and fully responsive to line current in one direction and a signal device connected in parallel with an adjacent rectifier element and fully responsive to line current in the opposite direction.
